UNITED STATES PATENT OFFICE.

JOHN WALTHER, OF BROOKLYN, NEW YORK.

SHEET-DELIVERY FOR PRINTING-MACHINES.

SPECIFICATION forming part of Letters Patent No. 371,721, dated October 18, 1887.

Application filed August 14, 1886. Serial No. 210,882. (No model.)

To all whom it may concern:

Be it known that I, JOHN WALTHER, of Brooklyn, county of Kings, and State of New York, have invented certain new and useful 5 Improvements in Sheet-Deliveries for Printing-Machines, of which the following is a specification.

This invention relates to an improved sheet-delivery for cylinder printing-presses, whereby 10 the fly heretofore commonly employed is dispensed with and the sheets delivered in a regular and uniform manner to the delivery-table.

The invention consists of a sheet-delivery attachment to printing-presses, which consists 15 of an intermittently rotating reel which takes the sheet from the impression-cylinder by a set of grippers and delivers it to a platform or table, in connection with suitable actuating and locking mechanisms, which will be fully described hereinafter, and finally pointed out in the claims.

In the accompanying drawings, Figure 1 represents a side elevation of the impression-cylinder of a printing-press with my improved 25 sheet-delivery attachment. Fig. 2 is a vertical longitudinal section of the same. Fig. 3 is a detail section of the impression cylinder and the delivery-reel, showing the latter in the act of taking up a printed sheet. Fig. 4 is a side view of the impression-cylinder and the mechanism for operating its grippers. Fig. 5 is an elevation taken from the opposite side of the machine, showing the mechanism for intermittently locking the delivery-reel. Fig. 30 6 is a sectional elevation showing the gripper-actuating mechanism of the cylinder and reel. Fig. 7 is a plan of the impression-cylinder and delivery-reel, showing the feed-board partly broken away; and Fig. 8 is a vertical section of the impression-cylinder and delivery-reel, showing the latter with the sheet gripped 40 and ready to be delivered on the table.

Similar letters of reference indicate corresponding parts.

Referring to the drawings, A represents the impression-cylinder of a printing-press with my improved sheet-delivery attachment, and B is the delivery-reel, which is composed of a number of disks, b, that are attached by set-screws to a shaft back of the impression-cylinder and located below the feed-board C of the press. The impression-cylinder A is pro-

vided with the usual grippers, g g, which are operated in the well-known manner by a gripper-bar, g', and fixed pins g², as shown in Fig. 6. 55 The grippers g g serve to take up the sheets from the feed-board C and conduct the same to the form. The delivery-reel B is also provided with grippers d, which are actuated by a stationary cam, d', that engages an anti-friction roller, d², of the gripper-arm d³, and by a spiral spring, d⁴, in the usual manner, as shown in Figs. 2 and 6. When the sheet has been printed, it is taken up by the grippers of the delivery-reel in the usual manner and carried along with the reel, and finally delivered to the delivery table or platform D, which is arranged below the delivery-reel and back of the impression-cylinder A, as shown clearly in the different figures of the drawings. 70

The impression-cylinder A receives continuous rotary motion by a suitable gear-wheel transmission from the driving-shaft of the printing-press. On the shaft of the impression-cylinder A is keyed a disk, F, which is provided 75 at its inner side with a cam-groove, f, that engages an anti-friction roller, f', of a lever, f², which lever is slotted, so as to clear the shaft of the impression-cylinder, its opposite end being pivoted to an oscillating lever, f³, that is 80 also pivoted at its longer end to the supporting-frame of the printing press. The upper forked end of the oscillating lever f³ serves to engage a crank-pin, f⁴, of the gear-wheel f⁴, which is keyed to the shaft of the delivery-reel and which serves to impart motion to the same. When the crank-pin f⁵ is engaged by the forked end of the oscillating lever f³, a pivoted and spring-actuated locking-lever, F', 85 engages, by a friction-roller, G, at its outer end, a notch, G', of a disk, G², which latter is keyed to the opposite end of the shaft of the delivery-reel B, so as to lock the delivery-reel in position ready for taking up the next sheet conducted to it by the rotation of the impression-cylinder. To accomplish this purpose a portion of the circumference of the motion-transmitting gear-wheel f⁴ of the delivery-reel B is mutilated—that is to say, the teeth at a portion of its circumference are cut away, as 90 shown in Fig. 1, so that it is retained in a position of rest by the locking-lever F', while the printing-cylinder continues its rotary motion. While the delivery-reel is thus locked the anti- 95

friction roller f' is at the dwell of the cam-groove f of the disk F . As soon, however, as the anti-friction roller f' passes from the position of rest in the cam-groove f to the eccentric portion of the groove, the gear-wheel f^4 of the delivery-reel B is turned by the levers f^2 and the crank-pin f^3 , and moved into gear with the transmitting gear-wheel on the shaft of the impression-cylinder, so that it continues its rotary motion. Simultaneously the locking-lever F' is unlocked from the notch of the disk G^2 .

As the delivery-reel is started, its gripper takes hold of the sheet carried along by the impression-cylinder, as shown in Fig. 3, and conducts it over the reel, which finally delivers it on the delivery-table. The intermittently-rotating delivery-reel and its locking mechanism, together with the mutilated gear-wheel on its shaft, impart thus the required motion by which the printed sheet is taken up from the cylinder, carried around with the delivery-reel, and delivered face upward on the delivery-table. As the disks of which the delivery-reel is composed form but narrow contacts with the printed face of the sheet, they exert but little, if any, blurring action on the same, which is further diminished by adjusting the individual disks of the reel in such a manner that they strike the outer or intermediate margins of the printing sheets. The sheet is delivered in an easy manner on the delivery-table, owing to the rotary motion of the delivery-reel and the small resistance exerted by the air on the sheet, so that the so-called "offset" of the printed sheet just delivered on the clean side of the next sheet is almost entirely obviated, owing to the fact that the forcible blows exerted on the sheets by the fly heretofore commonly in use in printing presses is dispensed with.

The essential feature of my invention is the intermittent stop that is imparted to the delivery-reel by the cam and lever motion on the shaft of the printing-cylinder and the mutilated portion of the gear-wheel on the shaft of the delivery-reel, in connection with the positive locking action produced by the locking-lever and notched disk on the shaft of the delivery-reel.

Another advantage of the attachment is that the delivery-reel and table, both being mounted below the feed-board, take up considerably

less room than the fly arrangement and delivery-table heretofore in use. Another advantage is the easy and uniform piling of the sheets which takes place, as there is but little resistance of the air to the sheet as the same is delivered by the reel onto the table, and which dispenses with the use of a special attendant or of a piling attachment.

Having thus described my invention, I claim as new and desire to secure by Letters Patent—

1. The combination, with a rotary impression-cylinder, of an intermittently-rotating delivery-reel having grippers, means for intermittently locking the delivery-reel, and a delivery-table below said reel, whereby the sheet is taken up by the reel as it is delivered by the impression-cylinder and conveyed to the delivery-table, substantially as set forth. 65

2. The combination of a rotary impression-cylinder, an intermittently-rotating delivery-reel having grippers, and means for intermittently locking the delivery-reel, so as to retain it in position for taking up the printed sheet, substantially as set forth. 75

3. The combination, with a continuously-rotating impression-cylinder, a grooved cam-wheel on the shaft of said cylinder, a lever operated by the cam-groove of said cam-wheel, a forked oscillating lever operated by said cam-lever, a delivery-reel, a mutilated gear-wheel having a crank-pin on the shaft of the delivery-reel, and a delivery-table, said printing-cylinder and delivery-reel being provided with grippers for taking up the printed sheet and placing the same on the delivery-table, substantially as set forth. 80

4. The combination of a continuously-rotating impression-cylinder, an intermittently-rotating delivery-reel, means, substantially as described, for intermittently rotating the delivery-reel, means, substantially as described, for locking said delivery-reel when at rest, and grippers for taking up the printed sheet and delivering the same to the table, substantially as set forth. 90

In testimony that I claim the foregoing as my invention I have signed my name in presence of two subscribing witnesses. 95 100

JOHN WALTHER.
